CHILD'S CRAWLER

Joel G. Silverman, New York, N. Y.

Application November 12, 1954, Serial No. 33,062

Term of patent 7 years

(Cl. D3—17)

FIG. 1

FIG. 2

Fig. 1 is a front elevational view of a child's crawler, showing my new design; and

Fig. 2 is a rear elevational view of the same.

Fig. 3 is a fragmentary front elevational view on an enlarged scale.

I claim:

The ornamental design for a child's crawler, as shown.
